(57) **CLAIM**

I claim the ornamental design for a stand for barbecue stove, as shown and described.

DESCRIPTION

FIG. 1 is a perspective view of a stand for barbecue stove showing my new design;

FIG. 2 is a front view thereof, the opposite side being a mirror image;

FIG. 3 is a left view thereof, the opposite side being a mirror image;

FIG. 4 is a top view thereof;

FIG. 5 is a bottom view thereof;

FIG. 6 is a perspective view thereof, with the shelves in an open position; and,

FIG. 7 is a perspective view thereof, in a collapsed position.
